UNITED STATES PATENT OFFICE.

ROBERT W. BALDWIN, JR., OF ISLIP, NEW YORK.

KEY RETAINER.

Application filed April 9, 1926. Serial No. 100,957.

This invention relates to a key, the general object of the invention being to provide means for holding a key in the keyhole of a lock so that it cannot fall out by the door 5 slamming or accidentally fall out through other causes.

This invention also consists in certain other features of construction and in the combination and arrangement of the several parts, to be hereinafter fully described, 10 illustrated in the accompanying drawings and specifically pointed out in the appended claim.

In describing my invention in detail, reference will be had to the accompanying drawings wherein like characters denote like or corresponding parts throughout the several views, and in which:—

Figure 1 is an edge view of the improved 20 key.

Figure 2 is an elevation.

Figure 3 is a section on line 3—3 of Figure 1.

As shown in these views, I form a recess 25 1 in the keyhole engaging part of the key A and place a bowed spring 2 therein, this spring projecting from the recess and having one end riveted or otherwise secured to the

key. Thus when the key is inserted into the keyhole of a lock, the spring will give sufficiently to pass into the hole, but it will frictionally engage the wall of the hole and thus yieldingly hold the key in the lock. 30 The spring will permit the key to be removed from the lock forcibly, but it will prevent the key from falling out of the lock when the door on which the lock is placed is slammed. The spring will prevent accidental removal of the key from the lock and the key will remain in place until it is 35 forcibly pulled from the lock.

It is thought from the foregoing description that the advantages and novel features of my invention will be readily apparent.

I desire it to be understood that I may 45 make changes in the construction and in the combination and arrangement of the several parts, provided that such changes fall within the scope of the appended claim.

What I claim is:—

A key having a recess formed in its key-hole engaging portion and a bowed spring having its ends placed in the recess with one end connected with the bottom of the recess.

In testimony whereof I affix my signature.

ROBERT W. BALDWIN, JR.
